[57] CLAIM

The ornamental design for an orthodontic bracket, as shown and described.

DESCRIPTION

FIG. 1 is a top, front and right side perspective view of an orthodontic bracket showing my new design; FIG. 2 is a top, rear and left side perspective view thereof;

FIG. 3 is a top plan view thereof, the bottom being a mirror image of that shown;

FIG. 4 is a front elevational view thereof;

FIG. 5 is a right side elevational view thereof; the left side being a mirror image of that shown;

FIG. 6 is a rear elevational view thereof;

FIG. 7 is a front elevational view of a second embodiment thereof, the difference being only that the second embodiment is a mirror image of the first embodiment; FIG. 8 is a top, front and right side perspective view of a third embodiment thereof;

FIG. 9 is a top, rear and left side perspective view of the embodiment of FIG. 8;

FIG. 10 is a top plan view of the embodiment of FIG. 8, the bottom being a mirror image of that shown;

FIG. 11 is a front elevational view of the embodiment of FIG. 8;

FIG. 12 is a rear elevational view of the embodiment of FIG. 8;

FIG. 13 is a right side elevational view of the embodiment of FIG. 8, the left side being a mirror image of that shown; and

FIG. 14 is a front elevational view of a fourth embodiment thereof, the difference being only that the fourth embodiment is a mirror image of the third embodiment.
